UNITED STATES PATENT OFFICE

CHARLES E. ADAMSON, OF MUNCIE, INDIANA

RETORT BURNER FOR SELF-HEATING SADIRONS

Original application filed February 5, 1925, Serial No. 7,003. Divided and this application filed August 6, 1925. Serial No. 48,517.

This invention relates to new and useful improvements in retort burners for self-heating sad-irons.

The primary object of this invention is to provide a retort burner which is especially adapted for use in sad-irons where gas and electricity are not available.

A further object of the invention is to provide means for converting industrial or denatured alcohol into gas for use in heating a sad-iron.

A further object of the invention is to provide means for preventing the return of the above-mentioned gas to the supply tank of the retort burner of the sad-iron.

A further object of the invention is to provide twin gas-producing means; a burner for each gas-producing means; and a control for each burner.

20 This is a divisional application of my pending application filed on February 5, 1925, and bearing Serial Number 7,003, on self-heating sad-irons.

Other objects and advantages of the invention will be apparent during the course of the following description.

In the accompanying drawings forming a part of this specification and in which like numerals are employed to designate like parts throughout the same,

Figure 1 is a side elevational view of the completely assembled sad-iron embodying this invention,

Figure 2 is a top plan view of the sad-iron illustrated in Fig. 1,

Figure 3 is a rear end elevational view of the sad-iron illustrated in Figs. 1 and 2,

Figure 4 is a vertical sectional view taken upon line IV-IV of Fig. 1,

Figure 5 is a vertical sectional view taken upon lines V-V of Fig. 1,

Figure 6 is a fragmentary top plan view, partly broken away, of the twin gas-producing means and the controls therefor,

Figure 7 is a fragmentary vertical sectional view of a portion of one of the gas-producing means with the control for the same,

Figure 8 is a top plan view of the bottom casting which forms a part of the body portion of the sad-iron,

Figure 9 is a top plan view of the body casting of the body portion of the sad-iron,

Figure 10 is a bottom plan view of the body casting illustrated in Fig. 9,

Figure 11 is a fragmentary rear end elevational view of the body casting illustrated in Figs. 9 and 10, and

Figure 12 is a fragmentary vertical sectional view taken upon lines XII-XII of Fig. 11.

In the drawings, wherein for the purpose of illustration is shown a preferred embodiment of this invention, the numeral 5 designates in its entirety the bottom casting of the sad-iron which has mounted thereon the body casting 6. This body casting 6 carries the burners, their gas-producing means, the controls for the burners, and the supply of denatured alcohol; all of these parts will be described in detail as the description proceeds. This body casting 6 has removably secured thereto the handle portion which is designated in its entirety by the numeral 7.

By referring to Fig. 8, it will be seen that this bottom casting 5 is provided with a plurality of fins 8 which are formed integrally therewith and cooperate with the longitudinally extending rib 9 for forming the flame pockets 10. The marginal edge of this bottom casting is formed with an upstanding flange 11 that is cut away or notched at 12 for forming air inlets for the flange pockets 10. The rear end of this casting 5 is provided with an upstanding ear 13 which is apertured at 14 and is internally screwed threaded for receiving the screw 15 that is employed for connecting the rear end of the body casting to the bottom casting. The longitudinally extending rib 9 is provided with an upstanding boss 16 adjacent the front end of the bottom casting 5 and this boss 16 has an internally threaded bore 17 for receiving the screw 18 which is employed for separably connecting the front ends of the body and bottom castings 5 and 6 respectively.

By referring to Figs. 9 to 12 inclusive, it will be seen that the body casting of the iron is of shell formation and includes the side walls 19, the rear end wall 20 and the pointed front end 21. This front end 21 is formed

with an overhanging wall 22 which is positioned substantially between the top and bottom edges of this casting 6. The vertical wall 23 extending between the overhanging wall 22 and the top edge of the casting is provided with a vertically extending bore 24 formed in a boss 25. This bore 24 is reduced in diameter at its lower end 24^a for forming a shoulder for the reception of the connecting bolt 18, best illustrated in Fig. 5. In Fig. 10, the casting 6 is illustrated as having the cored enlargements 26 formed with the side walls of the pointed front end 21 and located inwardly of the casting 6. These enlargements 26 are provided with burner openings 27 which are provided for uniformly heating the front end of the iron with respect to the remaining portion of the same. The tubular burner elements 28 are illustrated as having their front ends received within the pocketed portions 26^a of the cored enlargements 26 and are arranged with their burner openings 29 presented to the flame pockets 10 in the bottom casting 5. In Figs. 10, 11 and 12 the rear end wall 20 of this casting 6 is illustrated as being formed with the tubular bosses 30 which receive the rear ends of the burner tubes 28 which are closed by the removable caps 31 held in place by the screws 32. In Fig. 9, the top edges of the side walls 20 are illustrated as being provided with the notches 33 for permitting the entrance of air into the interior of the body casting 6. By referring to Figs. 5 and 9, it will be seen that the cored enlargements 26 are provided with vertically extending passageways 34 which are open at their upper ends 35 and communicate with the said cored enlargements 26 at their lower ends. The side walls 19 of this said body casting 6 are provided with air vents 36 which communicate with the passages 34, as best illustrated in Fig. 5.

Referring to Figs. 1 to 3 inclusive, it will be seen that a tank 37 is provided which has a removable filler cap 38 carried by the neck 39 of the tank by means of which denatured or industrial alcohol may be placed within the tank. Depending from the lower wall of this tank is a removable feed tube 40 which communicates with the intermediate portion of a substantially U-shaped converter trap coupling 41. Connected to the inner side faces of the ends of this U-shaped converter trap coupling 41 are the converter tubes 42 which extend longitudinally of the body casting 6 and are arranged in parallelism with each other. The front ends of these converter tubes 42 are threadedly connected with the valve blocks 43 which are provided with a connecting plate 44 which is secured to said blocks by the elements 45. This connecting plate 44 is apertured at 46 for receiving the bolt 47 illustrated in Figs. 1 and 5 as being employed for aiding in connecting the handle portion 7 of the iron to the body casting 6,

the said bolt 47 being threadedly connected at its lower end to the bore 24 of the boss 25 formed integrally with the body casting 6.

The construction of the valve blocks 43 is best illustrated in Figs. 5 to 7 inclusive. It will be seen that each block is provided with a tubular recess 47 within which the end of one converter tube 42 is received. Extending in axial alignment with this tubular pocket 47 is a reduced passageway 48 having a valve seat 49 at its outer end which is adapted to be engaged by the tapered end of the valve stem 50 which is threadedly connected to the block 43. Extending at right angles to this reduced passageway 48 is a second passageway 51 which extends downwardly and is arranged in axial alignment with the tubular passageway 34 formed in the body casting 6 of the iron and best illustrated in Fig. 5.

In Figs. 6 and 7, the converter tubes 42 are illustrated as being provided with fillers which consist of the spiral wire elements 52 which are alternately arranged with the twisted strands 53. It will be seen that these fillers extend from the converter trap coupling 41 to the valve block 43 in each converter tube 42.

The handle portion 7 includes a wooden hand grip 54 which has its opposite ends connected to the upstanding arms 55 of a heat-deflecting plate 56 by means of the bolt 57 which extends axially through the wooden hand grip 54. This heat-deflecting plate 56 is connected at its rear end to a lower heat-deflecting plate 58 by the bolt 59 and spacer 60. The front ends of these heat-deflecting plates 56 and 58 are connected by the bolt 47 and spacer element 61, the bolt 47 having been previously referred to as being threadedly received within the bore 24 of the boss 25 carried by the body casting 6. It will be seen that this bottom heat-deflecting plate 58 has its front end maintained in spaced relation to the connecting plate 44 for the valve blocks 43 by the spacer element 62. The bolt 47 forms a connection between the body casting 6 and the handle portion 7 of the sad-iron which will permit the lateral swinging of the handle portion, as illustrated in Fig. 2 by the arrow line. For the purpose of connecting the rear end of the handle structure 7 to the remaining portions of the sad-iron, a flexible latch member 63 is provided which is formed with the diverging legs 64 having their lower ends turned at right angles for being connected to the tubular bosses 30 by the screws 32 which fasten the ends of the burner tubes 28 and their caps 31 to the said tubular bosses 30. In Fig. 4 this latch member 63 is illustrated as having the notches 65 formed therein and arranged for alining with a cut-out portion 66 formed in the rear end of the heat-deflecting plate 58. The upper free end 63^a of this latch member is conveniently arranged in respect to the hand grip 54 for permitting the user

to flex the latch member toward the fuel tank 37 for disengaging the notches 65 of the latch member 63 for permitting the entire handle structure 7 to be swung laterally for exposing the interior of the body portion of the sad-iron.

The operation of this sad-iron for converting industrial or denatured alcohol into gas suitable to be burnt for heating the iron is as follows:—

It will be seen that the tank 37 may be filled to a desired level with industrial or denatured alcohol by removing the cap 38. After this tank 37 has been provided with alcohol, the latter will feed by gravity through the tube 40 into the converter trap coupling 41. This coupling will fill up with liquid alcohol until it reaches the level of the converter tubes 42 whereupon it will flow through these tubes, it being noted by inspecting Fig. 1 that the converter tubes 42 are inclined downwardly toward the front end of the sad-iron. The alcohol in passing through these converter tubes is caused to travel a tortuous path by the filler elements 52 and 53 located in these converter tubes. These filler elements are intended to produce a whirling motion by the spiral wires 52 and twisted strands 53. The flow of the alcohol into the burner tubes 28 and cored enlargements 26 is controlled by the valve stems 50 which may be rotated by means of the valve wheels 50^a carried by the projecting ends of these stems 50.

To start the heating of the iron, the valve stems 50 should be operated for permitting a small quantity of the alcohol in its liquid state to be fed into the flame pockets 10 formed in the bottom casting 5. The valves should then be shut off for preventing further feeding of the liquid fuel into the bottom casting and the liquid fuel that has been discharged should then be lighted. The burning of this liquid fuel causes the converter tubes 42 and the burner tubes 29 to be heated. The heating of the converter tubes 42 and the liquid fuel therein, will cause this fuel to vaporize or in other words, the liquid fuel will first start to boil and will then be changed into highly expanded gas or vapor. As this gas is produced, the valve stems 50 may be operated for withdrawing their tapered ends from the valve seats 49 for permitting this gas to pass through the passageways 48, in the valve blocks 43, and into the passageways 51. This gas passes downwardly through these passageways 51 and enters the tubular passageways 34 formed in the body casting 6. The travel of the gases through these passageways 34 causes the drawing in of air through the air vents 36. This mixed gas and air will produce a flame that is intensely hot and free from smoke or odor.

It will be understood that the filler elements 52 and 53 in the converter tubes 42 will retard the travel of the liquid fuel from

the tank 37 to the burners and this retarding of the travel of the fuel will permit the same to be converted into gas by the time it arrives at the valve blocks 43. The filler elements 52 and 53 and the converter trap coupling 41 will prevent the return of any of the gas into the tank 37.

It is now believed that the construction and operation of this sad-iron will be understood from the above detail description and that no further explanation is believed necessary.

It is to be understood that the form of this invention herewith shown and described is to be taken as a preferred example of the same, and that various changes in the shape, size, and arrangement of parts may be resorted to without departing from the spirit of the invention or the scope of the subjoined claims.

Having thus described my invention, what I claim as new and desire to secure by Letters Patent, is:—

1. In a gas producer of the type described, a fuel tank having a depending feed tube, a U-shaped coupling having its lower portion connected to said feed tube, converter tubes connected to the upper ends of said coupling, blocks supporting the other ends of the converter tubes, means within said converter tubes for diffusing liquid fuel therein, and valves in the blocks operable in proximity of the blocks for controlling the discharge of gas from said converter tubes.

2. In a gas producer of the type described, a fuel tank having a depending feed tube, a U-shaped coupling having its lower portion connected to said feed tube, converter tubes connected to the upper ends of said coupling, blocks supporting the other ends of the converter tubes, said converter tubes being supported at the upper end of the body portion of the body to be heated, means within said converter tubes for diffusing liquid fuel therein, and valves in the blocks operable in proximity of the blocks for controlling the discharge of gas from said converter tubes, the fuel diffusing means comprising contiguous alternate sections of twisted and spiral wire elements.

In testimony whereof I affix my signature.
CHARLES E. ADAMSON.
